UNITED STATES PATENT OFFICE.

IGNATIEUS A. HEBERT, OF NEW ORLEANS, LOUISIANA, ASSIGNOR TO THE HEBERT LIFE SAVING DEVICE CO., INC., OF NEW ORLEANS, LOUISIANA, A CORPORATION OF LOUISIANA.

LIFE-SAVING DEVICE.

1,347,372.

Specification of Letters Patent.

Patented July 20, 1920.

Application filed September 26, 1919. Serial No. 326,468.

To all whom it may concern:

Be it known that I, IGNATIEUS A. HEBERT, a citizen of the United States, residing at New Orleans, in the parish of Orleans and 5 State of Louisiana, have invented new and useful Improvements in Life-Saving Devices, of which the following is a specification.

The object of the device is to provide a 10 safety appliance for use in connection with automobiles and similar motor driven vehicles designed not only to act as a fender but also as means for grasping, holding and supporting the body of a pedestrian encountered by the machine for the purpose of avoiding the casualties ordinarily resulting from collision, and to this end the invention consists in a construction, combination and 15 relation of parts of which a preferred embodiment is illustrated in the accompanying drawings, it being understood that changes in the form, proportion and details, particularly as to the mounting and means of attachment, may be resorted to within the 20 scope of the appended claims, without departing from the principles involved.

In the drawings:

Figure 1 is a front view of the apparatus applied in the operative position to an automobile.

Fig. 2 is a plan view of the same.

Fig. 3 is a side view.

Fig. 4 is a vertical section on the plane indicated by the line 4—4 of Fig. 1.

Fig. 5 is a detail front view of one end of the apparatus to show particularly the means by which the grappling arms are normally restrained or held in their housed position.

Fig. 6 is a detail side view of the construction illustrated in Fig. 5.

Fig. 7 is a detail view of one of the grappling arms attached.

Fig. 8 is a similar view of one end of the retaining member.

In order that the apparatus may be applied as an attachment to automobiles and similar vehicles, now in use, it preferably embodies a frame or housing 10 supported 10 from the running gear by means of braces 11 which may have a certain degree of resiliency, sufficient to resist a shock tending to displace the same, but adapted to yield in order to cushion jars applied rearwardly to

the housing as by contact with an object obstructing the path of the machine, and pivotally mounted as at 12 and adapted normally to be retained within said frame or housing are the grappling arms 13 preferably of looped form so as to afford a relatively 55 broad bearing surface for contact with the body of a person that may be engaged thereby in the event of a collision.

Retaining means are employed for normally restraining the grappling arms or 60 maintaining them in their inoperative or housed positions, such as a rocker 14 having a pivotal mounting as at 15 upon the housing and provided with shoulders 16 for engaging terminal ears 17 on the grappling 65 arms, and the arms are yieldingly impelled toward each other for lateral swinging movement by means, for example, of coiled springs 18 which not only serve to close the arms or cause them to swing in opposite directions toward an object located between them, but to cause a compensatory movement of said arms, so that if the object so encountered is to one side of the center of the apparatus, thus restraining one of the 70 arms, the other will describe a greater arc so as to coöperate with the restrained arm in effectively grasping the body of a pedestrian that may be encountered in the progress of the machine.

Connected operatively with the rocker forming an element of the above mentioned retaining means for the grappling arms is an impact member adapted for contact with the person or other object in the path of the machine and consisting in the construction illustrated of a transverse bar or rod 20, preferably of a length approximately equal to the width of the machine and yieldingly supported for rearward movement when encountering an object, and as shown this impact member is supported by the rocker 14 by means of arms 21 which are deflected forwardly toward their lower ends so as to insure the contact with the obstruction of only 85 the bar or rod 20 which is held in advance of the other parts or members of the apparatus and is designed to be yieldingly positioned beneath the space embraced by the grappling arms when the latter have been released and closed around a body encountered by the machine so as to afford a rest or support for the body so engaged by the grap-

pling arms as will be understood by reference to Fig. 3 of the drawing wherein, in dotted lines there is shown the body of a pedestrian engaged by the grappling arms 5 and in a position to be caught up and assume a sitting position upon the impact member 20.

In practice it is preferred to extend the supporting arms downward from the cross 10 bar constituting the body of the rocker 14, and to provide said arms with bumpers or stop rods 22 extending rearwardly therefrom for terminal contact with the front of the machine or other fixed objects, so as to 15 limit the rearward or repressive movement of the impact member and thus prevent the withdrawal of said member from beneath the space embraced by the grappling arms when closed or in their operative or grappling 20 position. The impact member is yieldingly held in its normal or advanced position by means of a spring 25 arranged in or adjacent to the housing and bearing against a rear bracket 24 thereof, and this 25 spring in addition to holding the impact member advanced serves to maintain the arm retaining means in engaging position with reference to the terminal ears 17 of the arm, and also serves to readvance the impact member 30 and thus force it under the pedestrian engaged by the grappling arm, immediately following the impact which serves to move said impact member subject to limitation by the bumpers or stops 22, for the purpose 35 of lifting the body of the pedestrian or catching it up so as to support it when engaged by the grappling arms. In other words while the spring 23 which serves to actuate the rocker and the impact member is 40 adapted to permit of a sufficient yielding movement of the latter to release the grappling arms, it immediately returns the said impact member to a position which will enable it to perform the further function above 45 mentioned of supporting the body of the pedestrian encountered by the machine.

What I claim is:—

1. A safety device for automobiles having laterally movable coöperating grappling 50 arms for grasping the body of a person with which the vehicle collides, and an impact member movable rearwardly upon engagement with an object in the path of the vehicle for controlling the movement of the grappling arms, said impact member consisting of a cross bar and suspending arms and being yieldingly held in and returned to its

advanced position subsequent to impact with an object.

2. A safety device for automobiles having laterally movable coöperating pivotal grappling arms for grasping the body of a person with which the vehicle may collide and connected by a common spring to permit of their meeting at different points in their path of movement, and an impact member located below the plane of said arms and movable rearwardly upon engagement with an object in the path of the vehicle for controlling the movement of the grappling arms. 70

3. A safety device for automobiles having spring actuated independently pivoted grappling arms, means for normally restraining the arms, and a yielding impact member for actuating said means to release the arms for independent movement in paths determinable in extent by an interposed obstacle, said member having a supporting element located below the plane and coextensive with the path of movement of the arms and yieldingly held in advance of the normal positions thereof and beneath the space embraced thereby when closed. 75

4. A safety device for automobiles having spring actuated pivotal grappling arms, restraining means consisting of a rocker having shoulders for engaging said grappling arms, and a yielding impact member carried by said rocker in advance thereof. 80

5. A safety device for automobiles having a housing, yielding means for supporting the same from the running gear of a vehicle, spring actuated pivotal grappling arms mounted in the housing, a restraining means having a rocker provided with shoulders for 95 engaging said arms, and a yielding impact member supported by the rocker in advance thereof for communicating arm releasing movement thereto. 90

6. A safety device for automobiles having spring actuated grappling arms, restraining means for normally holding the grappling arms in their inoperative position, and consisting of a rocker for normally engaging the same, a cushioned rearwardly movable impact member depending from said rocker and arranged below the plane of the grappling arms, cushion springs for promptly returning said impact member to its normal position after repression by contact with an 105 opposing object, and means for limiting the rearward movement of the impact member. 110

In testimony whereof I affix my signature.

IGNATIEUS A. HEBERT.
